REMOVABLE BRIDGING PLUG FOR OIL
WELLS

Mertimer E. Norris, Bakersfield, Calif.

Application January 22, 1940, Serial No. 314,989

4 Claims. (Cl. 166—13)

My invention relates to a bridging plug for oil and gas wells and has for its principal objects, to generally improve upon and simplify the construction of the bridging plugs now in general use, to provide a plug having a chambered flexible member that is capable of being expanded as a result of pressure pumped into the chamber or chambers within said flexible member and which member, when expanded, adjusts itself to the irregular surface of the well hole and provides a fluid pressure tight joint between the plug and the hole and further, to provide a bridging plug of the character referred to that may be easily and conveniently run into the hole, expanded and afterwards withdrawn from the hole, and the use of which plug greatly facilitates the functions incident to the testing of the formations throughout the length of the well hole and at the same time eliminating the trouble-some and expensive cementing jobs that usually attend testing operations or the plugging of the well hole at different elevations.

A further object of my invention is, to provide a relatively simple and highly efficient bridging plug that is expanded by fluid pressure so as to completely bridge or seal the well hole at any desired point and said plug having associated therewith valvular means for controlling the fluid pressure utilized in expanding the plug and also for controlling any relatively high pressures that may develop in that portion of the well hole below the plug.

With the foregoing and other objects in view, my invention consists in certain novel features of construction and arrangement of parts that will be hereinafter more fully described and claimed and illustrated in the accompanying drawing in which:

Fig. 1 is a vertical section taken lengthwise 40 through the center of my improved plug and showing the same positioned in a well hole.

Fig. 2 is an enlarged horizontal section taken on the line 2—2 of Fig. 1.

Fig. 3 is a detail section of a punch pin that is 45 utilized for unseating the check valve that is positioned at the upper end of the plug.

Fig. 4 is a horizontal section taken on the line 4—4 of Fig. 3.

Fig. 5 is a vertical section taken through the 50 center of a box or coupling that may be used immediately above the plug and which box contains a check valve utilized for controlling the circulating fluid that is pumped into the well hole.

Fig. 6 is a vertical section taken lengthwise through the center of a modified form of the plug and which is used in making tests in the well hole.

Referring by numerals to the accompanying drawing and particularly to the form of expanding plug illustrated in Figs. 1 to 5 inclusive, 10 designates a metal tube that functions as a carrier for the various parts of the plug and the upper end of this tube is externally threaded so 10 as to be screw-seated in the internally threaded lower portion of a combined coupling and valve housing 11.

Arranged within member 11 is a partition 12 having an aperture that is normally closed by 15 an upwardly seating check valve 13 and the latter being normally held on its seat by an expansive coil spring 14. The lower end of this spring 14 rests on a partition 15 that is formed in the lower portion of member 11 and which is provided with a series of apertures 16.

The internally threaded upper end portion of coupling 12 is adapted to receive the threaded lower end of a drill pipe 17 or the like and which serves to lower the plug into the well hole and 25 to lift it therefrom.

The externally threaded lower end of tube 10 is screw-seated in a combined valve housing and coupling member 18 within which is formed a partition 19 having an opening and normally 30 resting on top of said partition 19 and closing the opening therein is a downwardly seating check valve 20 that is yieldingly retained on its seat by an expansive coil spring 21. The upper end of the coil spring bears against a partition 35 22 that is formed within the housing 18 and said partition being provided with apertures 24. The internally threaded lower portion of the coupling member 18 receives the threaded upper end of a circulation tube 25.

Positioned upon the tube 10 between the coupling members 11 and 18 is a substantially cylindrical body 26 of rubber or composition of which rubber is the principal ingredient and formed in the central portion of this body adjacent the 45 tube 10 is an angular chamber 27 that has communication with the passage through tube 10 by means of apertures 28 that are formed in the wall of the tube. Expansible body 26 is securely anchored to tube 10 by means 50 of flanges 29 that are formed on said tube 10, which flanges are preferably dovetail in cross section and which project into the body 26 above and below the chamber 27.

The end portions 30 of the expansible body 26 55

are tapered and enclosing same are metal caps 31 that taper slightly toward their outer ends.

Nuts 32 are screw-seated on the threaded portions of tube 10 and when said nuts are tightened 5 against the ends of the caps 31, the latter are clamped against the tapered ends of body 26, thereby cooperating with the dovetailed flanges 29 in anchoring said body to tube 10. The expansible body 26 may be of any desired length.

10 In Fig. 5 I have illustrated a downwardly seating check valve that may be utilized in the line 17 above the valve 13 for the purpose of controlling the circulation in its flow through the well hole and the drill pipe and also for controlling pressures that may develop in the well hole adjacent the plug.

This valve includes a housing 33 that is located in the line 17 above housing 11 and seated in the wall of said housing midway between its 20 ends is the lower outer end of an elbow fitting 34, the upper inner end thereof being provided with a valve seat 35. Adapted to rest on said valve seat is a ball check valve 36 from the top of which projects a short stem 37 carrying on its 25 upper end a head or knob 38 that is adapted to be engaged by a conventional expanding socket 39 and which latter may be run into the line 17 by means of a sand line or the like.

For the purpose of unseating check valve 13 to 30 relieve the pressure in the chamber 27 of the expanding member 26 in order that the plug may be pulled from the well, a ring 40 is seated in the lower end of the line 17 and said ring being provided with a spider 41 from which depends 35 a short pin or finger 42.

Thus when the line 17 carrying the ring 40 and pin 42 is lowered into the well hole for the purpose of removing the plug and the lower end of line 17 is screwed into the upper end of the 40 valve housing 11, finger 42 will unseat check valve 13, thus permitting pressure from the chamber 27 and within the tube 10 above the downwardly seating check valve 20, to pass upwardly into line 17 past the open valve 13.

45 In the use of the form of bridging plug just described, the drill tube or line that carries the plug is lowered into the well to the desired depth with the expansible body 26 deflated and circulation under pressure is now pumped downwardly through the line 17 and passes from tube 10 through the apertures 28 into chamber 27 so that, that portion of member 26 between the caps 31 will be expanded so as to make close contact with the adjacent surface of the well hole or with 50 the inner face of the casing in the event that casing has been run into the hole and thus, the flow or passage of oil, liquids, and gas through the well hole past the expanded member 26 is effectually prevented. The pressure pumped 55 downwardly through line 17 will open the upwardly seating check valve 13, but can not pass downwardly seating check valve 20.

In the event that pressure develops in the hole 60 below the plug and such pressure exceeds the pressure on the circulation pumped downwardly 65 into the expanding body 26, then such excess lower pressure will unseat upwardly opening check valve 20 and pass into tube 10, thereby increasing the pressure within the chamber 27 70 and consequently increasing the degree of pressure with which the expanded portion of member 26 engages the surface of the well hole.

When it is desired to pull the bridging plug 75 from the well hole, ring 40 carrying the finger 42 is inserted in the lower end of the line 17 and

the latter is lowered into the well and when the lower end of the line is screwed into the valve housing 11, pin 42 will unseat check valve 13, thereby relieving the pressure within the chamber 27 and permitting the expanded portion of 5 the body 26 to collapse and in such condition to be drawn from the well.

When the valve structure, Fig. 5, is used, the housing 33 is located in line 17 above the valve housing 11 and without the ball check valve 36, 10 the plug and valve housing are lowered into the well to the desired position. Circulation pumped downwardly through line 17 will discharge outwardly through elbow fitting 34 and flow downwardly past the unexpanded plug into the lower 15 portion of the well hole.

The use of the valve housing 33 and elbow 34 enables any liquid that may occupy that portion of the well hole into which the plug is positioned, to flow upwardly through elbow fitting 34 into 20 the pipe 10 and into the line 17.

Before starting the pump to force circulation fluid under pressure downwardly through line 17 to expand member 26, ball 36 is dropped into line 17 and after passing downwardly there- 25 through will rest on seat 35, thus providing a downwardly seating check valve and the circulation fluid under pressure will then flow from line 17 downwardly through the valve housing 33 into tube 10 and from thence into the cham- 30 ber 27 to expand member 26.

To lift the check valve 36 from its seat and remove the same from the line, a conventional expanding socket 39 is applied to the lower end of a sand line or the like and lowered into the 35 line 17 until said socket engages the head 38 on the stem 37 that projects upwardly from ball 36.

In Fig. 6 I have shown a form of plug that is especially designed for use in testing operations and this form of plug comprises an expansible 40 body 43 of rubber, having a centrally arranged chamber 44 and said body being anchored on a tube 45 with the ends of said body occupying 45 caps 46 that are held in position by nuts 47 screwed onto tube 45.

Located in tube 45 below the expanding body 43 is a downwardly seating check valve 48 that performs the same functions as check valve 20 previously described.

Formed through the wall of tube 45 within 50 chamber 44 are apertures 49 that are normally closed by spring pressed ball check valves 50 that are arranged for operation within a valve housing 51 and which latter is secured to tube 45 around the openings 49 therein.

Formed in valve housing 51 are apertures 52 that establish communication between the chamber within the valve housing and the chamber 44 in expansible member 43.

In the use of the plug just described, the line 60 55 carrying the plug is run into the well hole to the desired depth and any fluid or pressure in the well hole below the plug will flow upwardly past check valve 48 and thence upwardly through the line 45. When it is desired to expand the 65 plug, pressure is pumped downwardly through line 45 and such pressure being unable to pass downwardly seating check valve 48 will unseat valves 50 and flow through openings 49, thence through the openings 52 in valve housing 51, 70 thereby filling chamber 44 and expanding member 43 until the same is forced into close contact with the adjacent surface of the well hole.

After the tests have been made, a swage is run 75 downwardly through tube 45 so as to engage and 75

unseat check valves 50 and the pressure within the chamber 44 is now free to flow through the openings 49 into tube 45, thereby relieving the pressure in chamber 44 and permitting member 5 43 to return to its normal position.

When member 43 is expanded, the passage of liquid within the well hole above the plug downwardly into the well hole past said plug, is effectually prevented.

10 Thus it will be seen that I have provided a removable bridging plug for oil wells that is relatively simple in construction, inexpensive of manufacture and very effective in performing the functions for which it is intended.

15 Among the particular advantages of my improved plug are, the ability to conveniently raise and lower the plug to any desired point in the well for the purpose of making tests and for the bridging or plugging of the well hole at any 20 point without resorting to cementing operations which involve considerable time, labor and expense.

It will be understood that minor changes in the size, form and construction of the various 25 parts of my improved removable bridging plug for oil wells, may be made and substituted for those herein shown and described, without departing from the spirit of my invention, the scope of which is set forth in the appended 30 claims.

I claim as my invention:

1. A bridging plug for oil wells comprising a tube provided in its wall with an opening, an expandible member anchored on said tube, said 35 expandible member having a chamber that communicates with the opening in the wall of the

tube, an upwardly seating check valve in the tube above the expandible member, a downwardly seating check valve in said tube below said expandible member, a valve housing in the tube above said upwardly seating check valve, a tubular fitting within said valve housing, said fitting having an opening on the side of said valve housing communicating with the exterior of the tube and a valve seat within said valve housing on the inner end of said fitting and a valve removably positioned on said valve seat.

2. In a bridging plug for oil wells, a tube provided in its wall with an opening, an expandible member positioned on said tube and provided with a chamber that communicates with the opening in said tube, spaced anchoring flanges carried by said tube and embedded in opposite end portions of said expandible member, an upwardly seating check valve in the tube above said expandible member and a downwardly seating check valve in the tube below said expandible member.

3. A bridging plug for oil wells as set forth in claim 2 and with caps removably positioned on said tube and enclosing the ends of said expandible member.

4. In a bridging plug for oil wells, a tube, an expandible member carried thereby, a valve housing located in said tube above said expandible member, a tubular elbow fitting having one 30 end seated in the wall of said valve housing, the other end of said fitting being provided with a valve seat, a valve adapted to rest on said valve seat and a stem projecting upwardly from said valve.

35 MORTIMER E. NORRIS.
